UNITED STATES PATENT OFFICE.

SAMUEL L. KLEBER, OF PITTSBURGH, PENNSYLVANIA.

TRUNK.

1,265,212.

Specification of Letters Patent.

Patented May 7, 1918.

Application filed May 3, 1917. Serial No. 166,216.

To all whom it may concern:

Be it known that I, SAMUEL L. KLEBER, a citizen of the United States of America, residing at Pittsburgh, county of Allegheny, 5 and State of Pennsylvania, have invented certain new and useful Improvements in Trunks, of which the following is a specification.

This invention relates to trunks, boxes, 10 and other receptacles, more particularly trunks, and has for its object to provide a trunk, box or receptacle, with means in a manner as hereinafter set forth, for coupling and securing together the walls thereof 15 without the employment of tacks or screws and further whereby the corner edges of the trunk, box or receptacle are reinforced.

In the manufacture of trunks, the body portion, which is formed of a series of panels, forming the walls and bottom of the 20 trunk, are nailed together and after which reinforcing strips are secured to the outer sides of the panels by means of nails and this manner of setting up the body portion 25 is open to the objection that the nails not only weaken the panels, but furthermore than that it requires considerable time which is objectionable especially in the manufacture of moderate price trunks as 30 such time is a considerable item of expense.

To overcome the foregoing objection relative to the weakening of the panels and to reduce the cost of manufacturing are the primary objects of this invention and which 35 are attained by the employment of corner elements for not only coupling and securing the walls of the trunk, box or receptacle together, but which further act as a means to set up an interior and exterior reinforcement for each wall as well as reinforcing the 40 edges of said body portion.

Further objects of the invention are to provide a trunk, box or receptacle, which is simple in its construction and arrangement, 45 strong, durable, reinforced at its corner edges, readily set up and comparatively inexpensive to manufacture.

With the foregoing and other objects in view the invention consists of the novel construction, combination and arrangement of parts, as hereinafter more specifically described and illustrated in the accompanying

drawings, wherein is shown an embodiment of the invention, but it is to be understood that changes, variations and modifications 55 can be resorted to which come within the scope of the claims hereunto appended.

In the drawings wherein like reference characters denote corresponding parts throughout the several views:—

Figure 1 is a perspective view of a trunk in accordance with this invention.

Fig. 2 is a sectional elevation, broken away, of the body portion of the trunk.

Fig. 3 is a vertical sectional view, broken 65 away, of the body of the trunk.

Fig. 4 illustrates a modified form of combined coupling and securing element.

Fig. 5 illustrates, in section, still another modified form of combined coupling and 70 securing element.

Referring to the drawings in detail 1 denotes the lid of the trunk and which is hinged in the known manner to the body portion of the trunk which comprises a front 75 wall 1', a rear wall 2, a pair of end walls 3 and a bottom 4.

Associated with the front and rear walls and the bottom are a pair of longitudinal corner combined coupling and securing 80 strips, one of which overlaps the front marginal portion of the bottom and the lower marginal portion of the front wall and the other of which overlaps the rear marginal portion of the bottom and the lower marginal portion of the rear wall.

Associated with the bottom and the end walls are a pair of transversely disposed combined coupling and securing strips, one of which overlaps one end marginal portion 90 of the bottom and the bottom marginal portion of one end wall and the other of which overlaps the other end marginal portion of the bottom and the bottom marginal portion of the other end wall.

Associated with the front, rear, and end walls, are four vertically disposed combined coupling and securing strips, two of which overlap the front side marginal portions of the end walls and the end marginal portions 100 of the front wall and the other two overlap the rear side marginal portions of the end walls and the end marginal portions of the rear wall.

The longitudinal, transverse and vertical combined coupling and securing strips are employed for not only coupling the panels of the body portion of the trunk, said panels forming the walls and bottom of said body portion, but are also employed for securing the same together.

The longitudinal strips are equal in length to the length of the front and rear walls, the vertical strips are equal in height to the height of the front and rear walls, and the transverse strips are of a length equal to the length of the end walls.

As the longitudinal strips are similar in construction to the vertical strips and as the vertical strips are similar in construction to the transverse strips, but one combined coupling and securing strip will be described, for the reason that the description of it will apply to each of the others.

Each of the combined coupling and securing strips is formed from a single length of metallic material bent to form an inner section and an outer section. The outer section is L or angle shaped and comprises a vertical and a horizontal leg 5, 6, respectively. The inner section consists of an angle shape portion formed of legs 7, 8, and an angle shape portion formed of legs 9, 10. The angle or L-shaped portions of the inner section are disposed at right angles with respect to each other. The legs 7, 8, bear against the inner faces of the legs 5, 6. The leg 7 is of less length than the leg 5 and the leg 8 is substantially of the same length as the leg 6. The leg 6 is connected with the leg 8 by an inwardly extending protuberance 11 which constitutes a securing means. The leg 9 is arranged parallel to the leg 8, but spaced therefrom, and is of less length than the length of the leg 8.

The leg 7 terminates in the leg 9 and the latter is disposed at right angles with respect to the former. The leg 9 also extends at right angles with respect to the leg 5. The leg 10 opposes the leg 5 and extends toward said leg 5 at a slight inclination.

The free terminus of the leg 5 is bent upon itself to form a protuberance 12 which constitutes a securing means. The free terminus of the leg 10 is bent inwardly to provide an offset, as at 13, which constitutes a securing means. The offset 13 opposes the protuberance 12.

The leg 8 in connection with the legs 7 and 9 forms a pocket 14 and the leg 5 in connection with the legs 9, 10 forms a pocket 15.

The leg 7 is the bottom of the pocket 14 and the leg 9 is the bottom of the pocket 15.

Each of the panels which form the walls and bottom of the body portion of the trunk can be formed of a single piece of material or laminated strip. In Fig. 2 the panels are

shown as formed of a single strip of material while in Fig. 3 each of the panels is laminated.

The pockets 14 and 15 are adapted to receive the panels which are forced into said pockets and after being forced therein the protuberances 11 and 12, as well as the offset portion 13, are embedded in the panels and act as securing means to prevent separation of the panels.

The strips not only couple the panels together but also reinforce the inner and outer faces thereof, and further secure the panels in position.

The pocket 14 is disposed at right angles with respect to the pocket 15 and as the walls of the pocket 14 are reinforced by the legs 5 and 6 the exterior corners of the trunk are made very strong.

Overlapping the combined coupling and securing strips are edge pieces 16, which are secured to the body portion of the receptacle or trunk.

Secured to each corner of the body of the trunk, as at 18, are corner pieces 19.

In Fig. 4 of the drawings instead of utilizing a flat strip of material to provide the combined coupling and securing strips the material is slightly corrugated, as at 20, which increases the strength of the material.

The employment of the combined coupling and securing strips in a manner as stated overcomes the necessity of using reinforcing strips which are tacked to the panels of the trunk, and further the nailing of the body portion together.

In Fig. 5 of the drawings a modified form of combined coupling and securing strip is illustrated with but one wall of one pocket reinforced. In Fig. 5 the strip comprises an angle shape portion formed of legs 21, 22, and a channel portion formed of a bottom 23 and walls 24, 25. The wall 25 terminates in the leg 21. The bottom 23 opposes and is spaced from the leg 22. Protuberances are indicated at 26, 28 and an offset at 27. The wall 25 and a portion of the leg 21 reinforces one wall of the pocket provided by the channel portion.

What I claim is:

A coupling strip for the purpose set forth comprising a length of metallic material bent upon itself to provide a vertical and a horizontal pocket disposed at right angles with respect to each other, the outer wall of said vertical pocket being perpendicular and having its upper end bent inwardly against its inner face to provide means capable of embedding in the outer face of a side wall of a receptacle, the inner wall of said vertical pocket permanently extending throughout at an inclination toward the outer wall of said pocket and further having its upper end bent inwardly at a greater inclination.

than the remaining portion of said wall to provide means capable of embedding in the inner face of a side wall of a receptacle, the outer wall of said horizontal pocket being of greater length than the inner wall and having its free terminus bent inwardly to provide means to embed in the outer face of the bottom of a receptacle, the said means em-

bedding in the said wall and bottom securing the coupling strip in position.

In testimony whereof I affix my signature in the presence of two witnesses.

SAMUEL L. KLEBER.
